UNITED STATES PATENT OFFICE.

SIDNEY J. RUMBOLD, OF PATERSON, NEW JERSEY.

WINDOW WEDGE.

Application filed December 17, 1925. Serial No. 76,039.

The present invention relates to improvements in window wedges, an object of the invention being to provide a device of this character which will serve the dual purpose 5 of limiting the relative sliding movement of the sashes, and of preventing rattling of the sashes when the latter are partially opened. The wedges are equipped with means for limiting the relative sliding movement of the sashes so that the sashes may be left partially opened without any danger of 10 an intruder gaining entrance through the window.

It is a further object of the invention to 15 provide a wedging means which may be conveniently swung to inoperative position to permit free sliding movement of the sashes, and a wedging means which will be of simple, practical construction, which will 20 be rugged, durable and efficient in use, and which is well suited to the requirements of economical manufacture.

With the above noted and other objects 25 in view, the invention consists in certain novel features of construction and combinations and arrangements of parts, as will be more fully hereinafter set forth and pointed out in the claims. The invention may be 30 more fully understood from the following description in connection with the accompanying drawings, wherein—

Fig. 1 is a plan view of a window frame mounting a pair of sashes and showing my 35 improved wedges in applied position, a portion of the window frame being broken away for the sake of clearness.

Fig. 2 is a sectional detail cut through the channel portion of the window frame and showing the normal position of the sashes.

Fig. 3 is a similar view showing the sashes 40 partially opened to an extent limited by the wedges.

Fig. 4 is a fragmentary perspective view 45 of a portion of one of the sashes, showing one of the wedging members swung to inoperative position.

Fig. 5 is a view similar to Fig. 4, but showing the wedge in operative position.

In the drawings I have used the reference 50 character 10 to designate a conventional window frame formed at its side edges with channels 11 in which upper and lower sliding sashes 12, 13 of conventional construction

are mounted. The upper edge of the lower sash carries a bevelled outwardly facing rail 55 14 adapted to mate with a bevelled inwardly facing rail 15 in the customary manner, so that when the sashes are in normal closed position, the rails engage and prevent rattling of the sashes.

The present invention is more particularly concerned with the provision of wedging members 16 of general V-shape, each having one leg attached to a leaf 17 of a leaf hinge, the other leaf 18 of which may be screwed 60 to the side frame bars of the inner face of the sash 12 as indicated at 19. The V-shaped wedging member is of spring metal, preferably of spring steel, and the free leg thereof is formed with a lip 20 at its free 65 end.

As seen in Figs. 4 and 5, the hinge plate 17 may be folded inwardly to move the wedge member 16 out of the path of the rail 14 of the lower sash, or may be swung over 70 on the opposite plate 18 to position the wedging member 16 in the path of said rail. As the sashes are relatively slid, the rail 14 engages the free arms of the wedging 75 members 16, and tends to fold the wedging members, as best seen in Fig. 3, the lips 20 serving to positively limit the relative sliding movement of the sashes with the parts in the position of Fig. 3. The inherent resiliency of the wedging member 16 will serve 80 to prevent rattling of the sashes, and the lip 20 prevents the window from being entered by an intruder; inasmuch as it locks the sashes against relative movement to an extent which would permit an intruder to 85 gain access.

For the purpose of washing the windows, it is merely necessary to swing the hinge plate 17 to the position of Fig. 4, thereby carrying the wedge members out of the path 90 of the rail 14.

Various changes and alterations might be made in the general form and arrangement of parts described, without departing from the invention. Hence I do not wish to limit 100 myself to the details set forth, but shall consider myself at liberty to make such changes and alterations as fairly fall within the spirit and scope of the appended claims.

I claim—
1. A window wedge unit adapted to be

attached to a sliding sash and including a leaf hinge, a V-shaped wedging member of spring metal having one end attached to one leaf of the hinge, and including a laterally projecting lip at its other end.

2. The combination with a pair of sliding sashes, of wedging members secured to one

sash and adapted for wedging engagement with the rail of the other sash, said wedging members including V-shaped strips of spring metal, and lips projecting from the free end of the strips for limiting the relative sliding movement of the sashes.

SIDNEY J. RUMBOLD.
